UNITED STATES PATENT OFFICE.

JOSEPH PERCY REMINGTON, OF PHILADELPHIA, PENNSYLVANIA, ASSIGNOR TO
REMINGTON MANUFACTURING COMPANY, OF PHILADELPHIA, PENNSYLVANIA, A CORPORATION OF PENNSYLVANIA.

MEANS AND METHOD FOR SUPPLYING LIQUID FUEL TO EXPLOSIVE-MOTORS.

1,373,911.

Specification of Letters Patent. Patented Apr. 5, 1921.

Application filed May 26, 1919. Serial No. 299,836.

To all whom it may concern:

Be it known that I, JOSEPH P. REMINGTON, a citizen of the United States, and a resident of Philadelphia, county of Philadelphia, and State of Pennsylvania, have invented an Improvement in Means and Methods for Supplying Liquid Fuel to Explosive-Motors, of which the following is a specification.

10 My invention has for its object the provision of suitable means for supplying gasoline or other explosive fluid to a motor from a source of supply which is located at a lower level than that of the carbureter of 15 the motor, and which means shall be simple in construction, positive in action, inexpensive to manufacture and requiring very little space for installation.

A further object of my invention is to 20 provide a system for raising the gasoline or other fluid to an elevation sufficient to insure the flow, by gravity, to the carbureter in such a manner that the flow shall be practically continuous during the operation of 25 the motor, so as to avoid the necessity of large reservoirs or tanks for directly supplying the carbureter with the fluid; this being accomplished by providing a direct pumping operation as distinguished from a continuous suction and with the result that approximately only sufficient gasoline is 30 drawn to the higher level of the motor as would be required by the said motor under its maximum consumption. The pumping 35 action is secured by providing the suction from a single cylinder of the motor, so as to obtain positive intermittent action as distinguished from a practically continuous suction which would be secured from the 40 intake manifold of a multiple cylinder motor. While in my improved system it is intended that the supply of gasoline shall be maintained approximately in accordance with the consumption, it is manifest that the 45 rate of consumption with the same engine varies under different speeds and loads and consequently provision is made for operation between maximum and minimum requirements; and the devices are so constructed that this condition is maintained 50 by control of the liquid supply, to prevent, on the one hand, an abnormal rise of the liquid in the system and, on the other hand, an abnormal return of the liquid to the stor-

age tank, during any variation in the operation of the motor. 55

With the above and other objects in view, the nature of which will be more fully understood from the description taken in connection with the drawings, the invention 60 consists in the novel construction of apparatus as hereinafter more fully described and defined in the claims.

Referring to the drawings: Figure 1 is a diagrammatic elevation illustrating the 65 application of my invention to a motor and supply tank; Fig. 2 is a vertical sectional view of the means for controlling the flow of the gasoline; Fig. 3 is a vertical section taken on the line 3—3 of Fig. 2, but on a 70 larger scale; and Fig. 4 is a perspective view of the valve piece shown in Figs. 2 and 3, which is directly operated by the intermittent pressure of the motor cylinder.

2 illustrates a multiple cylinder motor of 75 any suitable character, such as employed in automobiles or motor boats, and in which the several cylinders 3 may be supplied from a common carbureter 4, through the usual manifold system. 5 is the reservoir or supply tank and which is shown at a lower level than the carbureter 4, and from which the gasoline or other explosive fluid is required to flow through pipes 7 and 8 to the carbureter under the regulation of the control mechanism 6 which is arranged at a higher elevation than the carbureter and made effective by the varying pressure, due to the pulsations supplied through a pipe 9 from one of the plurality of cylinders 3. 80 90

In the operation of this apparatus, the single cylinder 3 operates as a pump to supply suction and pressure alternately through the pipe 9, these actions of suction and pressure taking place alternately in a 95 rapid intermittent manner during the running of the motor. The construction of the device 6 is such that the suction impulses produced in the pipe 9 are intermittently made effective to create vacuum impulses 100 within the chamber of the said device, whereas the pressure impulses in the pipe 9 are excluded as far as possible from the said chamber of the device. In this manner, the gasoline is caused to flow from the 105 tank 5 upwardly through the pipe 7 and into the chamber of the device 6, and thence, by gravity, to pass through pipe 8 to the

carbureter 4. The device 6 is provided with valve means to prevent a back flow of the gasolene to the tank 5 except at certain times and at the same time is provided with means 5 for permitting access of atmospheric pressure to its chamber alternately with the suction impulses, these suction impulses and atmospheric admissions being produced in rapid succession during the normal running 10 of the motor.

More specifically describing the internal construction of the control device 6, reference will be made to Figs. 2, 3 and 4 which illustrate a preferred construction. 10 is a tubular body which is closed at top and bottom to provide a float chamber. At the bottom, this body 10 is screwed into a base 11 provided with an outlet 12 for connection with the pipe 8 which leads to the carbureter 4; and this outlet 12 is provided with a check valve 13 which permits free flow of gasolene from the float chamber to the carbureter, but prevents any suction within the float chamber drawing the gasolene from 25 the carbureter through the pipe 8 into the float chamber. Screwed into the bottom of the base 11 is a bushing 14 having a screw threaded nipple for connection with the supply pipe 7 leading from the reservoir 5. 30 The bushing 14 is recessed on its upper part to provide an enlarged chamber 15, and when screwed into place within the bottom of the base 11 it is made to clamp a strainer 16 of suitable material in position to prevent any 35 particles of dirt finding its way from the reservoir 5 to the float chamber and thence to the carbureter. The base piece 11, immediately above the strainer 16, is provided with a vertical aperture 17 opening into the 40 float chamber within the tubular body 10. The top of the tubular body 10 is screwed tightly into a head 18 which is provided with a vertical passage 23 and a horizontal passage 20, said passages communicating 45 with each other, as shown. The horizontal passage 20 is provided at one end with a valve seat 21 and at the other end with a valve seat 22, said valve seats facing in opposite directions. The passage 20 and its 50 valve seat 21 are in communication with a threaded nipple 19 with which the pipe 9 (Fig. 1) is connected. 25 is a valve stem preferably square in cross section (Fig. 3) and has upon one end a valve piece 26 and 55 on the other end a valve piece 27, said valve pieces respectively adapted to coöperate with the seats 21 and 22 aforesaid. The length of the valve stem 25 is such that the valve pieces 26 and 27 are separated a 60 slightly greater distance than are the seats 21 and 22, so that when the valve piece 26 seats tightly upon the seat 21, the valve piece 27 is clear of its seat 22, as illustrated in Fig. 2. Similarly, when the valve piece 65 27 is seated tightly upon its seat 22, the

valve piece 26 will be off its seat 21. This valve piece is put into rapid reciprocation during the normal running of the motor, as it makes one reciprocation with each reciprocation of the piston in the cylinder with 70 which it is in communication through the pipe 9.

A float 28 is arranged within the float chamber formed by the tubular body 10 and this float is of elongated shape in a vertical 75 direction, so that the diameter of the body 10 is relatively small. The upper end of the float 28 is provided with a conical valve piece 29 the extension of which is guided in the aperture 23. The lower edge of this 80 aperture constitutes a valve seat 24 in which the conical valve piece 29 seats when the float is sufficiently raised by the presence of gasolene in the float chamber, as indicated in Fig. 2. When this condition takes place, 85 the suction produced by the motor does not become effective upon the contents of the float chamber because the valve piece 29 acts as a check valve to close the communication with the float chamber. The lower part of 90 the float 28 is similarly provided with a conical valve piece 30 and a guide extension 31 therefrom extends downward into the vertical passage 17 to hold the float centrally of the float chamber. If the gasolene 95 within the float chamber becomes lowered sufficiently, the float will be lowered also and the valve piece 30 will seat upon the upper edge 32 of the aperture 17 and act as a check valve to prevent the gasolene in the 100 float chamber flowing back into the tank 5.

The operation will now be understood: Assuming that the motor is in operation with the preliminary supply of gasolene in the carbureter, the alternate suction and 105 pressure which is produced in the cylinder 3 connecting with the pipe 9, will exert alternately a suction and pressure through said pipe in synchronism with the reciprocations of the piston in the motor, and this will be with every reciprocation of the piston, whether the motor be a two-cycle or 110 four-cycle machine. The higher the speed of the motor, the more rapid will be the alternations between suction and pressure in 115 the pipe 9. The effect of the alternating suction and pressure in the pipe 9 is to reciprocate the valve piece 25. On the suction stroke of the motor, the valve piece 25 is moved to the right (Fig. 2) 120 and this enables the suction to extend into the float chamber, causing inflow of gasolene until the float 28 is lifted sufficiently to close the aperture 23. The suction impulses will cause the gasolene to flow from the reservoir 125 5 through pipe 7 and upwardly into the float chamber, and in this case the gasolene will pass from the chamber 15 through the strainer 16 and passage 17 into the float chamber. If the level of the gasolene is suffi- 130

ciently low to allow the valve piece 30 to seat upon its seat 32, then said valve piece acts as a check valve, and while permitting the inflow of the gasoline, prevents the 5 backflow thereof into the reservoir 5. On the pressure stroke of the motor, the valve piece 25 is moved to the left, to the position shown in Fig. 2, in which case the pressure is shut off from the float chamber and at the 10 same time said float chamber is in communication with the atmosphere by reason of the fact that the valve piece 27 is moved away from its seat 22. When this action takes place, the gasoline within the float 15 chamber is free to pass by the check valve 13 and through pipe 8 to the carbureter 4, it being understood that the float controlling the valve of the carbureter regulates the delivery of gasoline to the carbureter in accordance with its requirements. If during 20 the normal operation of the apparatus, the gasoline in the float chamber rises to the level indicated in Fig. 2, it will raise the float and, in so doing, cause the valve piece 25 25 to seat at 24 to close the passage 23, so that no further suction can exert its influence within the float chamber to increase the height of the gasoline therein; and this condition will be maintained until the level of 30 the gasoline in the float chamber descends sufficiently to lower the float, either by the gasoline passing to the carbureter or back through pipe 7 to the reservoir, or partly to each of these causes. Under the normal 35 operation of the motor, at something less than its maximum speed and for all lesser speeds, the valve piece 30 will act as a check valve to prevent back-flow of gasoline from the float chamber to the reservoir. For all 40 higher speeds of the motor than those indicated above, the check valve piece 30 will also act as a check valve to prevent back-flow of the gasoline except when the gasoline should rise above the normal level intended 45 within the float chamber, in which case, the float being lifted, raises the valve piece 30 and permits backflow of the gasoline until sufficiently lowered that the valve piece 30 may again seat and act as a check 50 valve. Should the motor continue to operate at high speed and thereby provide suction upon the float chamber in excess of what is normally necessary, then in such case, the gasoline will rise to a level sufficient 55 to lift the float and its valve piece 29 to shut off the suction by sealing the passage 23, and maintaining this condition until the level of the gasoline lowers sufficiently to again insure valve piece 30 seating and 60 acting as a check valve. The valve piece 29 acts as a check against abnormal rise of the gasoline and loss by drawing it out of the float chamber. By means of the devices above referred to, the level of the gasoline 65 is maintained within reasonably close levels,

which insure an average normal static head sufficient to insure proper supplying of gasoline to the carbureter under all possible conditions.

I have shown a vent aperture 36 (Fig. 70 2) opening from the float chamber into the valve seat 22 which, when the valve piece 27 is off its seat, will permit ready access of air into the float chamber to break any vacuum that might be therein and to insure 75 the flow of the gasoline to the carbureter. While the use of this vent aperture 36 makes the apparatus more sensitive, I have found in practice, that it may be dispensed with and reliance for the breaking 80 of the vacuum be placed upon the air passages 20 and 23, since any vacuum which might be in the float chamber would draw the air at atmospheric pressure through said 85 passages past the valve piece 29 and into the float chamber, as the float descends.

While I have shown the float 28 and its valve pieces 29 and 30 of such proportions that approximately a half inch movement to the float would be required to unseat one 90 valve piece and seat the other, I do not limit myself to these proportions, and hence the construction may be such that a lesser movement of the float may be provided for.

By reference to Figs. 3 and 4, it will be 95 seen that the stem 25 of the valve pieces 26 and 27 is made square in cross section and the purpose of this is that it shall so fit the aperture 20 at four places, that it is properly guided thereby while permitting the 100 passage of air and thereby obviates the necessity of additional guiding means.

Apparatus of this character requires very little additional space under the engine hood of an automobile, because the control devices 105 6 are only approximately six inches long by one inch in diameter and, therefore, it has been found exceedingly easy to install apparatus of this character in the available space in automobiles.

I have described my improved method and means in that particularity which I deem to be the best exposition of my invention, and that which I prefer in commercial practice, but I do not restrict or confine myself to 115 the minor or secondary details, as such variations may be resorted to as matters of mechanical skill and without a departure from the spirit of the invention.

Having now described my invention, what 120 I claim as new and desire to secure by Letters Patent is: —

1. Means for supplying a liquid fuel to an explosive motor, comprising the combination of a motor provided with a carbureter, a reservoir for liquid fuel at a lower elevation than the carbureter, a chamber at a higher elevation than the carbureter, a pipe leading from the lower part of the chamber to the carbureter, a pipe leading from the 125 130

lower part of the chamber to the reservoir, a pipe leading from the upper part of the chamber and communicating with a cylinder of the motor whereby rapid alternating impulses of suction and pressure are exerted in said pipe during the normal operation of the motor, valve means for permitting the liquid fuel to flow from the reservoir into the chamber and normally preventing flow in the opposite direction, and a valve device for alternately providing communication between the chamber and the atmosphere on the one hand and the pipe communicating with the motor cylinder during its suction cycle on the other hand, said valve device arranged for synchronous reciprocation with each change from pressure to suction in the cylinder of the motor, and vice versa.

2. The construction specified in claim 1, having the reciprocating valve devices consisting of two oppositely arranged valve pieces permanently connected at a distance apart different from the distance apart of the valve seats therefor, ports in communication with the valve seats and with the liquid fuel receiving chamber, the spaces beyond valve seats being respectively in communication with the atmosphere and with the pipe leading to the cylinder of the motor, whereby the reciprocation of the valve pieces close communication with the atmosphere when making communication between the motor cylinder and the chamber, and vice versa.

3. The structure specified in claim 1, having the chamber provided with a vertically movable float having at its upper end a valve piece for opening and closing communication between the chamber and the valve device which controls communication with the cylinder of the motor, whereby when the liquid fuel has risen in the chamber to a maximum level, further suction from the cylinder of the motor will be ineffective upon the contents of the chamber until the level of the liquid fuel therein has become sufficiently lowered.

4. The invention specified in claim 1, wherein the chamber is provided with a float having valve pieces at both top and bottom for respectively controlling the communication between the chamber and the cylinder of the motor to prevent suction within the chamber when the liquid fuel stands therein at a maximum level, and for controlling the return flow of the fuel from the chamber to the reservoir to limit the extent of the fall of the liquid fuel within the chamber, said float controlled valve pieces operating alternately according to the position of the float and the level of the liquid fuel within the chamber.

5. The invention according to claim 1, wherein a check valve movable under the action of the varying liquid level within the

chamber is provided for interrupting the communication between the cylinder and interior of the chamber whereby the suction produced by the motor is not permitted to affect the liquid within the chamber after it reaches a maximum level.

6. The invention specified in claim 1, further having the chamber provided with a float and valve piece to close communication with the upper part of the chamber when a maximum level of liquid fuel is contained therein, whereby a normally closed or open communication may be automatically provided with the chamber according to the level of the liquid fuel therein and without interfering with the normal rapid reciprocation of the valve device which is effected by the alternating pressure and suction effects produced within the motor.

7. In a device for controlling the supply of liquid fuel to a motor, the combination of a float chamber having at the bottom an intake port and a discharge port, each provided with check valves for respectively permitting the inflow of fluid to the float chamber and outflow from the float chamber through the discharge port, a passage from the upper part of the float chamber having communication both with the atmosphere and with an inlet port arranged for communication with a source of alternate suction and pressure, two check valves connected together and movable as a unit for alternately shutting off communication between the chamber and the atmosphere while opening communication between the chamber and the inlet port leading to the source of suction and pressure and vice versa, and a float and valve operated thereby within the float chamber for controlling communication with the upper part of the float chamber whereby communication thereof with the inlet port leading to the source of suction and pressure may be shut off automatically whenever the liquid within the chamber rises to a maximum level.

8. The invention specified in claim 7, wherein the check valve for controlling the intake port at the bottom of the float chamber is connected with the float, whereby it is automatically opened when the float rises and closed when the float descends.

9. The herein described method of supplying the liquid fuel to the carburetor of the motor from a source of fuel at a lower level than the carburetor, which consists in supplying liquid fuel to a chamber arranged at a higher level than the carburetor, maintaining communication between the lower part of the chamber and the source of liquid fuel, producing in the immediate upper portion of the chamber alternate impulses of pressure and suction synchronously with the varying pressure and suction within the cylinder of the motor, controlling the action

of said suction and pressure of the motor upon the contents of the chamber by intermittently shutting off the pressure effect of the cylinder and piston of the motor from the chamber and simultaneously opening communication between the chamber and the atmosphere to cause the liquid fuel to flow by gravity to the carbureter and alternately therewith closing communication between the chamber and the atmosphere and causing thereby the suction effect of the cylinder and piston of the motor to be communicated to the interior of the chamber, whereby vacuum impulses are provided within the chamber and act to raise the liquid level therein, the fuel content of said chamber

being intermittently influenced by the suction impulses of the motor and the atmospheric pressure controlled as to times of action by the pressure impulses of the motor. 20

10. The method specified in claim 9, further characterized by employing the rising fluid level within the chamber to actuate means to close communication between said chamber and the source of suction by the motor, whereby the said suction is prevented from affecting the contents of the chamber when the liquid therein is at a maximum level. 25

In testimony of which invention, I here- 30 unto set my hand.

JOSEPH PERCY REMINGTON.
